DESIGN FOR A COMBINED BOTTLE AND CONTAINER THEREFOR

Otto S. Garry and Percy M. Brown, New York,
N. Y.

Application May 6, 1938, Serial No. 77,023

Term of patent 14 years

To all whom it may concern:

Be it known that Otto S. Garry and Percy M. Brown, citizens of the United States and residents of New York city, in the county of Kings and State of New York, have invented a new, original, and ornamental Design for a Combined Bottle and Container Therefor, of which the following is a specification, reference being had to the accompanying drawing forming part thereof, and in which,

Fig. 1 is a perspective view of a combined bottle and container therefor embodying our new design, showing the device with the cover removed and the bottle in an elevated position;

Fig. 2 is a top plan view thereof in closed position;

Fig. 3 is a bottom plan view thereof;

Fig. 4 is a top perspective view thereof with the cover and bottle removed; and

Fig. 5 is a perspective view of the cover of the design shown in Fig. 2.

We claim:—

The ornamental design for a combined bottle and container therefor, substantially as shown and described.

OTTO S. GARRY.
PERCY M. BROWN.
